CLIMBING AND SPINNING TOY

Steffen P. Németh, Chicago, Ill.

Application February 25, 1950, Serial No. 146,298

2 Claims. (Cl. 46-61)

1

This invention relates to a rotatable toy having the dual characteristics of a climber and of a spinner. It may be produced from different materials such as plastic, wood, etc., and involves in its construction an assembly of but the fewest parts. Its construction is such that it is adapted to be spun as a top or be rotated to climb vertically upon a cord. No operation need be performed in order to convert the toy from one use to the other.

Certain suggestive embodiments of this invention are illustrated in the accompanying drawing wherein—

Figure 1 is a view in perspective of the toy as it appears when used as a climber;

Fig. 2 is a side elevation of the toy when partly surrounded by a ribbon preparatory to its use as a spinner;

Fig. 3 is a longitudinal section, taken on line 3—3 of Fig. 1;

Fig. 4, which is a view similar to Fig. 3, shows a modified construction of the toy; and

Fig. 5 is a view similar to Fig. 2, showing the toy of Fig. 4.

Referring first to the construction of Figs. 1-3, I have provided two like hollow cones C and C', of plastic or the like, each having at its apex an inserted steel fitting 41 provided with a spinning point 42 which is exposed upon the cone end. For the two cones there are provided heads H and H' each in the form of a disc having a peripheral recess to form a shoulder 13 whereon the base end 14 of the cone may be seated and to which it may be secured with the aid of an appropriate adhesive. Extending axially from each disc toward the other for end engagement therewith is a short hub 15 whereby to maintain the discs spaced apart slightly to provide between them a deep narrow groove g.

The head H' is also provided with a lateral passageway 18 which communicates with the groove g at a point which is close to the hub 15. At the center of this head is an axial opening for receiving a hollow rivet 20 which is extended through the head H as well. In this way the two heads are axially aligned, and by enlarging opposite ends of the rivet to engage outer faces of the heads the two hollow cone bodies C and C' are secured together as a unit.

The peripheral surfaces of the two heads are desirably serrated at 25 thereby to provide a traction lane. The maximum diameters of the heads are such as to substantially coincide with the diameters of the cones at their base ends 14 which are desirably rounded at their points of

junction to facilitate the assembly of the cones. The heads are provided with a central recess 26 which is of a diameter slightly greater than the diameter of the rivet 20 so as to provide a shoulder 27 which is of a diameter slightly less than the diameter of the rivet 20. The rivet 20 is inserted through the heads H and H' and the cones C and C' so as to engage the shoulder 27 of the heads and the shoulder 13 of the cones. The rivet 20 is then secured in place by a suitable adhesive.

The heads H and H' are provided with a peripheral edge of a thickness which is slightly greater than the thickness of the cones C and C' so as to provide a shoulder 28 which is of a diameter slightly less than the diameter of the rivet 20.

The heads H and H' are provided with a peripheral edge of a thickness which is slightly greater than the thickness of the cones C and C' so as to provide a shoulder 28 which is of a diameter slightly less than the diameter of the rivet 20.

The heads H and H' are provided with a peripheral edge of a thickness which is slightly greater than the thickness of the cones C and C' so as to provide a shoulder 28 which is of a diameter slightly less than the diameter of the rivet 20.

At the junction of the cones C and C' and the heads H and H' there is provided a central passageway 18 which is of a diameter slightly greater than the diameter of the rivet 20 so as to provide a shoulder 27 which is of a diameter slightly less than the diameter of the rivet 20. The rivet 20 is inserted through the heads H and H' and the cones C and C' so as to engage the shoulder 27 of the heads and the shoulder 13 of the cones. The rivet 20 is then secured in place by a suitable adhesive.

At the junction of the cones C and C' and the heads H and H' there is provided a central passageway 18 which is of a diameter slightly greater than the diameter of the rivet 20 so as to provide a shoulder 27 which is of a diameter slightly less than the diameter of the rivet 20. The rivet 20 is inserted through the heads H and H' and the cones C and C' so as to engage the shoulder 27 of the heads and the shoulder 13 of the cones. The rivet 20 is then secured in place by a suitable adhesive.

In the operation of assembling the two cones and heads, a cord c is placed between the heads with its end portion inserted through the passageway 18. The cord end is then tied into a knot at 26 so as to be held against endwise movement through the passageway. The free end portion of the cord is later coiled around to lie wholly within the groove g. If it is desired to use the toy as a climber, the cord is rhythmically reciprocated vertically to induce rotation of the toy with each gravitational descent thereof whereby to accumulate a store of kinetic energy sufficient to produce thereafter a climbing of the toy on the cord.

To operate as a top, a ribbon r is wound around the serrated traction lane in the central portion of the toy and over the groove g (see Fig. 2). In this operation the cord c remains wholly within the groove. The free end of the wound ribbon is then held securely while the toy is

cast outwardly and downwardly to land, either end down, upon the hard smooth surface selected for the spinning operation. It will be noted that the ribbon tends to enter the groove g (see Fig. 2) while engaging the serrations 25 whereby the friction therebetween is enhanced. This is particularly desirable in the case of a plastic construction where the exterior surface is rather smooth and slippery.

Referring now to Figs. 4 and 5, the construction here is much the same except that the two cones C and C' are solid as would be the case if made of wood. These cones are interconnected by a dowel pin 31 which is extended into coaxial openings 32 in the two cones as far as permitted by the depth of such openings. The two cones are then maintained slightly spaced apart. A suitable glue or cement is used to secure the dowel pin to each of the cones between which is a deep narrow groove g' that extends inwardly to the pin 31. A cord c by which the toy may be spun after the manner of a top is coiled around within the groove and its inner end portion is extended into a lateral passageway 35 that is provided at one point adjacent the dowel pin to be clamped in place thereby.

In this construction I provide at each cone apex a steel fitting 41 having an exposed spinning point 42 adapted to engage with the surface whereon the toy is to be spun. A pair of such fittings, one at each end of the toy, assures a long

life therefor. In the central portion of the toy each cone is formed with an annular recess 45 to cooperate with the other in providing a shallow guideway into which a ribbon r may be fitted and wound thereupon. When this is done, the cord c is first coiled around within the groove g' so as to be confined wholly therein. When the ribbon is wound around within the guideway, the toy is adapted to be used as a top in the manner already described.

I claim:

1. A climbing-spinning toy, comprising a pair of opposed and co-axially disposed conical bodies, substantially complementary circular heads individually and fixedly engaged with the adjacent ends of the conical bodies, axially arranged and disposed hubs on the adjacent and outer sides of said heads endwise abuttingly engaged and fixedly interconnected and relatively spacing the heads whereby to form therebetween a narrow circumferential channel opening outwardly onto said heads and terminating at and about said endwise abuttingly engaged hubs, an inner portion of said channel communicating with a lateral way in one of said heads for engagement therethrough and securement therein of one end portion of a cord wound within and about said channel, and the outer peripheries of said circular heads being each correspondingly inset with relation to the peripheral portions of the adjacent ends of said conical bodies whereby to form a circumferentially disposed channel of a depth less and a width greater than that of said first channel for the reception therein of a wound flexible ribbon independently of the wound cord.

2. A climbing-spinning toy, comprising a pair of opposed and co-axially disposed conical shell-like bodies, substantially complementary circular heads individually and fixedly engaged with the adjacent ends of the conical shell-like bodies, axially arranged and disposed hubs on and extended laterally from the adjacent and outer sides of said heads endwise abuttingly engaged and

fixedly interconnected and relatively spacing the heads whereby to form therebetween a narrow circumferentially disposed channel opening outwardly onto said heads and terminating at and about said endwise abuttingly engaged hubs, an inner portion of said channel communicating with a lateral way in one of said heads for engagement therethrough and securement therein of one end portion of a cord wound within and about said channel, and the outer peripheries of said circular heads being each correspondingly inset with relation to the peripheral portions of the adjacent ends of said conical shell-like bodies, whereby to form a circumferentially disposed channel of a depth less and with a width greater than that of said first channel and communicating therewith for the reception therein of a wound flexible ribbon independently of the channel received wound cord, said ribbon when wound about and within the last mentioned channel being free for deflection into the mouth portion of the first mentioned channel whereby to increase its frictional engagement with said circular heads.

STEFFEN P. NÉMETH.
